No. 883,472.

PATENTED MAR. 31, 1908.

W. H. NEHER.

OIL GASIFIER.

APPLICATION FILED FEB. 26, 1906.

UNITED STATES PATENT OFFICE.

WILLIAM H. NEHER, OF INGLEWOOD, CALIFORNIA.

OIL-GASIFIER.

No. 883,472.

Specification of Letters Patent. Patented March 31, 1908.

Application filed February 26, 1906. Serial No. 302,892.

To all whom it may concern.

Be it known that I, WILLIAM H. NEHER, a citizen of the United States, residing at Inglewood, in the county of Los Angeles and State of California, have invented a new and useful Oil-Gasifier, of which the following is a specification.

In a previous application of mine, filed Oct. 10, 1905, Serial No. 282,108, I have shown and described an apparatus for converting crude oil or distillate into a permanent gas which is designed particularly for use with explosive engines, the necessary heat for the initial vaporizing and the ultimate gasifying of the oil being derived from the exhaust gas of the engine.

The present invention relates to an apparatus of similar type, but of an improved construction.

One of the main objects of the present invention is to heat the air to a high degree before it is admitted to the vaporizing member, and another object of substantially equal importance is to provide means for causing this heated air and the exhaust gas to be brought into more intimate contact with the oil on the vaporizing member and to also expose a greater area of oil in contact with the air than is obtained by the apparatus in the previously described application, or by any other apparatus of which I am aware.

The accompanying drawings illustrate the invention and referring thereto:—Figure 1 is a vertical cross section through the apparatus, showing it connected with the cylinder of an explosive engine. Fig. 2 is a vertical cross section through the apparatus on line x^2-x^2 Fig. 1. Fig. 3 is a horizontal cross section through the apparatus on line x^3-x^3 Fig. 2. Fig. 4 is a view similar to Fig. 2 but partly in elevation, illustrating another form of vaporizing member and flanges. Fig. 5 is a horizontal cross section through the apparatus on line x^5-x^5 Fig. 1.

The apparatus comprises a base 1, having a cupped upper portion 2 with an inwardly directed flange 3 forming a central circular opening 4. Mounted on the cupped portion 2 is a dome 5 having flanges 6 which are detachably fastened to flanges 7 on the cupped portion 2 by thumb screws 8. The dome 5 is covered with a metal jacket 9 with an intervening asbestos heat insulation 10. The upper end of the dome has a lifting ring 11, and in order to determine the temperature

within the dome, a thermometer 12 may be inserted in the upper end of the dome, as shown in Fig. 1.

Within the dome 5 nesting therewith is a cylindrical vaporizing member 13, the lower edges of which rest upon the flange 3. The upper wall of the vaporizing member 13 is slanted, as shown in Fig. 2. Preferably formed integrally with the vaporizing member 13 is a diametrical partition or web 14, the lower portion of which extends below the cylindrical portion of the vaporizing member 13 into the base 1, dividing the latter into two chambers 15 and 16. The upper edge of the web 14 terminates short of the inclined upper wall of the vaporizing member, thus forming an opening 17 giving communication between the two chambers in the vaporizing member 13.

Preferably cast integrally with the web or partition 14 is a conduit or pipe 18, the upper end of which has an extension 19 which projects beyond the upper edge of the web 14 and through and beyond the upper inclined wall of the vaporizing member, as clearly shown in Figs. 1 and 2. The upper end of the extension 19 terminates short of the upper wall of the dome. The lower end of the conduit 18 has an extension 20 which projects through and below the base of the chamber 1 and is threaded for a nut 21, by means of which the conduit, web, and vaporizing member (all of which are integral) are rigidly held securely in position. A pipe 22 is connected to the threaded extension 20 for the purpose of conveying gas from the apparatus to the cylinder 23 of the engine, the pipe 22 connecting with a pipe 24, the lower end of the latter connecting with an air inlet pipe 25, having a valve 26 for regulating the amount of air admitted to mix with the gas which is conducted through the pipe 22, so that the proper mixture of air and gas is allowed to enter through the pipe 24 into the cylinder.

Formed externally on the walls of the vaporizing member is a series of flanges 27. These flanges are preferably cast integrally with the vaporizing member and they extend clear to the walls of the dome 5. Each flange is very slightly dished, as shown, and has a slightly raised rim 28 which lies close to the wall of the dome 5. Each flange also has a segmental opening 29, as shown in Fig. 3. The flanges are arranged in two sets, one set

100

105

110

slanting in one direction and the other set slanting in the opposite direction, as shown in Fig. 2. The openings 29 of one set of flanges are arranged next to one side wall, the openings 29 of the other set are arranged diametrically opposite. There is thus a vertical tortuous passage for hot air up through the interior of the dome formed by the staggered openings 29, and for the downward 10 passage of oil formed by the slanting flanges.

At one side of the partition 14 the base 1 has an enlargement 31 which is closed by a plate 32, and a butterfly valve 33 is arranged in this space to regulate the passage of exhaust gas from one chamber to the other. The valve 33 has a stem 34 which passes through a stuffing-box 35 and has a handle 36. A spring 37 serves to frictionally hold the valve in the position set. The valve 33, when placed vertically, alines with the edge of the partition 14 and divides the chamber 15 from the chamber 16.

A pipe 38 connects the chamber 15 with the cylinder 23 and serves to conduct the exhaust from the cylinder to the chamber 15.

A pipe 39 connects the chamber 16 with a T 40, the latter connecting with a vertical pipe 41 which discharges the exhaust gas from the apparatus. Extending down through the pipe 41 is an air intake 42, the lower end of which passes through the T 40 and is connected by piping 43 with the chamber 30, as shown in Figs. 1, 2 and 5. The chamber 30 has a drain pipe 44 provided with a valve 45.

An oil pipe 46 extends up through the chamber 30 close against the inside of the dome 5, the flanges being cut to permit the passage of the pipe, and the pipe 46 has a curved upper end 47 adapted to discharge 40 the oil down on the top flange as shown in Fig. 2. The lower end of the pipe 46 is connected by a pipe 48 with a valve 49, and in order to maintain the proper head of oil to insure its delivery from the upper end of the

pipe 46, a looped pipe 50 is provided, one run of which communicates with the valve 49. 45 50 and 51 designate the circuit terminals of the loop 50 which are connected with the oil supply source and surplus tank not shown.

The loop 50 is always kept filled with oil, and the desired amount may be admitted to the pipes 48 and 46 by means of the valve 49. The oil which is not admitted through the valve 49 passes up and down through the 55 loop 50 into the overflow tank.

In operation the exhaust gas from the cylinder 23 passes through the pipe 38 into the chamber 15 and, with the valve 33 closed, the exhaust gas passes up through the interior of the vaporizing member 13 on one side of the partition, through the openings 17 at the upper end and down on the other side of the partition into the chamber 16, thence through the pipe 39 into the T 40, thence up 60 through the pipe 41 from which it discharges

from the apparatus. If the valve 33 is fully opened, then the exhaust gas passes direct from the chamber 15 to the chamber 16 and thence into the pipe 41. The amount of exhaust gas which is admitted to the interior of the vaporizing member depends upon the position in which the valve 33 is set, and as stated, if the valve is closed, all of the exhaust gas will pass up and down through the vaporizing member, while, if the valve is partially opened, only part of the exhaust gas will pass through the vaporizing member, the remainder passing directly into the chamber 16 and thence out through the pipe 41. Air is drawn through the pipe 42, which lies with 70 in the pipe 43, into the pipe 18 and thence into the chamber 30. From the chamber 30 it passes up into the lowermost chamber within the dome 5 below the lowest flange, passes to the opposite side of the vaporizing member, then up through the opening 29 of the superposed flange into the next space; it then passes to the other side of the dome and passes up through the opening 29 of the next 75 higher flange into the next space and so on back and forth, the air taking a tortuous path back and forth across the space within the dome 5, but externally of the vaporizing member, thus traversing each of the many chambers formed by the flanges and then issues through the top flange into the upper 80 part of the dome. The air which is drawn through the pipe 42 becomes very highly heated while traversing the pipe 41 through which the exhaust gas is escaping, and therefore this air, before it enters the interior of the dome, is extremely hot.

The oil which is admitted from the pipe 46 drops onto the upper flange and, flowing around both sides of the conduit, falls down 105 through the opening 29 onto the next lower flange, and the oil spreads out on this flange and flows in a reverse direction to the lower part of the flange, then through the opening 29 of the flange onto the next succeeding flange, and so on down through the successive chambers formed by the flanges. Any oil or residue which, during this passage, is not converted into gas, drops into the chamber 30 from which it may be discharged from 110 time to time through pipe 44. The oil in taking this downward tortuous passage spreads out in a thin film over the flanges so that a great area of it is exposed to the direct action of the hot air which is taking the same 115 tortuous passage, but which is working up in the opposite direction, so that the oil is formed into a vapor or gas, the purer portion of which assembles at the upper part of the dome 5, and this mixture of gas and heated 120 air is drawn by the suction of the engine down through the pipe 19 through the pipe 22 into the cylinder of the engine, and the gas in its downward passage through the pipe 18 is thus kept at the proper tempera- 125 130

ture, by reason of the additional heat which is imparted to it by the heat of the exhaust gas which has a circuit up and down through the interior of the vaporizing member on both sides of the partition 14.

I have found in practice that the hot air which rises from the chamber 30 is alone sufficient to vaporize the oil, but by my construction as high a degree of heat may be obtained as desired by reason of the great amount of additional heat which may easily be obtained by deflecting all or even part of the exhaust gas into the interior of the vaporizing member.

15 A very important feature of this invention is the heating of the air within the pipe 41, and another important feature to be observed in this construction is that the flanges prevent the direct passage of air from the bottom to the top of the dome, as they are extended clear to the walls of the dome and form a large number of communicating chambers which cause the hot air to work its way by degrees to the top of the dome and thus 25 come into contact with a great area of the oil with which it is thus necessarily in contact for a considerable time causing it to impart as much of its heat as possible to the oil to vaporize the same. The flanges being 30 large also cause the oil to be spread out thinly and to be exposed over a great area to the action of the hot air, thus greatly promoting the efficiency of the apparatus.

If desired, the flanges may be made spirally, 35 as shown in Fig. 4, in which case the heated air will have an upward helical travel, while the oil will have a downward helical travel, the action of the heated air on the oil being practically the same as in the previously described construction.

While the helical flanges in this modification form what might be termed a single continuous flange, and a continuous spiral chamber, just as the threads of a screw are sometimes referred to as the "thread" of the screw, I consider the construction to be the equivalent of the series of flanges of the previous form, and in the claims I use the term "flanges" as including the helical flanges 50 as well as the flanges of the previous form, and thus I consider the helical flanges as forming chambers which communicate. Moreover the operation of the helical construction is substantially the same, and the result obtained is substantially the same as in the previous form.

It is considered much preferable to perform the vaporization by the heated air and to admit only enough exhaust gas to the interior of the vaporizer to keep the gas which has been formed by the heated air warm, thus obviating heating the metal too high by the exhaust gas which causes the oil to carbonize and collect on the metal. By admitting

only this amount of exhaust gas to the vaporizer and relying substantially exclusively on the heated air for accomplishing the vaporization the oil does not carbonize and the apparatus is thus kept very much cleaner than otherwise.

70 What I claim is:—

1. A base, a vaporizing member above the base, a dome housing and nesting with the vaporizing member, flanges on the vaporizing member extending to the wall of the dome and forming a series of chambers, the flanges having openings whereby a tortuous passage is formed, means for conveying fuel to the flanges, means for conducting heated air through the tortuous passage, and means 80 for conveying gas from the interior of the dome.

2. A base, a vaporizing member above the base, a dome housing and nesting with the vaporizing member, means for conducting 85 exhaust gas through the vaporizing member, flanges on the vaporizing member extending to the wall of the dome and forming a series of chambers, the flanges having openings whereby a tortuous passage is formed, means 90 for conveying fuel to the flanges, means for conducting heated air through the tortuous passage, and means for conveying gas from the interior of the dome.

3. A base, a vaporizing member above the base, a dome housing and nesting with the vaporizing member, flanges on the vaporizing member extending to the wall of the dome and forming communicating chambers, means for conducting fuel to the flanges, and 100 means for conducting hot air to the passages, so that as the fuel flows down the flanges it is brought into direct contact with the hot air which is passing up through the chambers.

105 4. A base, a vaporizing member above the base, a dome housing and nesting with the vaporizing member, means for conducting exhaust gas through the vaporizing member, flanges on the vaporizing member extending 110 to the wall of the dome and forming communicating chambers, means for conducting fuel to the flanges, and means for conducting hot air to the passages, so that as the fuel flows down the flanges it is brought into 115 direct contact with the hot air which is passing up through the chambers.

5. A base, a vaporizing member above the base, a dome housing and nesting with the vaporizing member, flanges on the vaporizing member extending to the wall of the dome and forming communicating chambers, means for conducting fuel to the flanges, and means for conducting hot air to the passages, so that as the fuel flows down the flanges it is 120 brought into direct contact with the hot air which is passing up through the chambers, the vaporizing member having a diametrical 125

partition which gives an up and down circuit of the exhaust gas in its passage through the vaporizing member.

6. A base, a vaporizing member above the base, a dome housing and nesting with the vaporizing member, flanges on the vaporizing member extending to the wall of the dome and forming communicating chambers, means for conducting fuel to the flanges, and means for conducting hot air to the passages, so that as the fuel flows down the flanges it is brought into direct contact with the hot air which is passing up through the chambers, the vaporizing member having a diametrical partition which gives an up and down circuit of the exhaust gas in its passage through the vaporizing member, the partition extending into the base chamber and partially dividing the same into two sections, a valve in said base chamber adapted to regulate the passage of exhaust gas from one section to the other of the base chamber, and thereby regulating the amount of said exhaust gas which is deflected into the vaporizing member.

15 7. A base, a vaporizing member above the base, a dome housing and nesting with the vaporizing member, flanges on the vaporizing member extending to the wall of the dome and forming communicating chambers, means for conducting fuel to the flanges, means for conducting hot air to the passages, so that as the fuel flows down the flanges it is brought into direct contact with the hot air which is passing up through the chambers, the vaporizing member having a diametrical partition which gives an up and down circuit of the exhaust gas in its passage through the vaporizing member, the partition extending into the base chamber and partially dividing the same into two sections, a valve in said base chamber adapted to regulate the passage of exhaust gas from one section to the other of the base chamber, and thereby regulating the amount of said exhaust gas which is deflected into the vaporizing member, an auxiliary chamber in the base communicating with the lowest chamber in the dome, an exhaust pipe for discharging the exhaust gas from the base chamber, and an air pipe within the exhaust pipe for conveying air to the auxiliary chamber.

8. An automatic oil gasifier comprising a vaporizer member over which the oil passes, means for conducting a heating gas through the vaporizer for heating the walls thereof, and means for conducting vapor generated by the vaporizer back through a long passage the outer wall of which has an extensive area in contact with the heating gas in the vaporizer for converting the vapor into a permanent gas.

9. An automatic oil gasifier comprising a vaporizer over which the oil passes, a partition forming two communicating chambers in the vaporizer, means for conducting a

heating gas through said chambers, and means in the partition for conducting vapor generated by the vaporizer between said chambers to form it into a permanent gas.

10. An automatic oil gasifier comprising a tubular vaporizer for converting oil into a vapor, means for confining the vapor in contact with the external wall of the vaporizer, a passage having an extensive area within the vaporizer through which passage said vapor is conducted for converting said vapor into a permanent gas, and means for passing a heating gas through the vaporizer externally of said passage.

11. An automatic oil gasifier comprising a tubular vaporizer for converting oil into a vapor, a removable dome covering the vaporizer for confining the vapor, a passage having an extended area within the vaporizer, through which passage said vapor is conducted for converting said vapor into a permanent gas, and means for passing a heating gas through the vaporizer externally of said passage.

12. An automatic oil gasifier comprising a cylindrical vaporizer for converting oil into a vapor, means for confining the vapor in contact with the external wall of the vaporizer, a conduit having a great area within the vaporizer and extending substantially longitudinally through the vaporizer for conducting the vapor through the interior of the vaporizer, and means for conducting a heating gas through the interior of the vaporizer but externally of said conduit, for heating the walls of the vaporizer and said conduit whereby the latter heats the vapor in it and forms a permanent gas thereof.

13. An automatic oil gasifier comprising a tubular vaporizer for converting oil into a vapor, a removable dome covering the vaporizer for confining the vapor, a conduit extending through the vaporizer and having an extensive area within the vaporizer for conducting the vapor through the interior of the vaporizer, and means for conducting a heating gas through the interior of the vaporizer but externally of said conduit.

14. An automatic oil gasifier comprising a tubular vaporizer for converting oil into a vapor, cylindrical means for confining the vapor around the outside of the vaporizer, a conduit extending through the vaporizer longitudinally for conducting vapor therethrough, and means for conducting a heating gas through the vaporizer externally of the conduit.

15. An automatic oil gasifier comprising a tubular vaporizer for converting oil into a vapor, cylindrical means nesting with the vaporizer for confining the vapor around the outside of the vaporizer, a conduit extending longitudinally through the vaporizer through the whole length of the vaporizer for conducting vapor therethrough and

- means for conducting a heating gas through the vaporizer externally of the conduit, the conduit having an extension, the upper end of which lies near the upper boundary of the confining means.
16. An automatic oil gasifier comprising a base, a vaporizer above the base, means forming an air-tight chamber around the vaporizer, means for conducting oil into said chamber into contact with the vaporizer, means for conducting a heating gas through the vaporizer to heat the walls thereof and convert the oil into a vapor, means having an extensive area within the vaporizer for conducting the vapor through the interior of the vaporizer to form the vapor into a permanent gas, and means for combining air with the permanent gas after it has passed from the vaporizer.
17. An automatic oil gasifier comprising a base, a vaporizer above the base, means for dividing the vaporizer into two chambers which communicate at the top of the vaporizer, means dividing the base into two chambers which communicate with the respective chambers in the vaporizer, a dome supported by the base and housing and nesting with the vaporizer, a conduit extending longitudinally through the vaporizer from end to end and through the base for conducting vapor from the dome through the interior of the vaporizer, and means for conducting a heating gas through the base and vaporizer externally of said conduit.
18. An automatic oil gasifier comprising a base, a vaporizer above the base, means for dividing the vaporizer into two chambers which communicate at the top of the vaporizer, means dividing the base into two chambers which communicate with the respective chambers in the vaporizer, a dome supported by the base and housing and nesting with the vaporizer, a conduit extending concentrically through the vaporizer and the base for conducting vapor from the dome through the interior of the vaporizer, and means for conducting a heating gas through the base and vaporizer.
19. An automatic oil gasifier comprising a vaporizer over which the oil passes, means for conducting a heating gas through the vaporizer for heating the walls thereof, means having an extensive area within the vaporizer for conducting vapor generated by the vaporizer back through the heating gas in the vaporizer whereby said vapor is exposed to a great heating area in the vaporizer for converting the vapor into a permanent gas, means for mixing the permanent gas with air, and means for conducting the permanent gas thereto.
20. An automatic oil gasifier comprising a tubular vaporizer over which the oil passes, means for conducting a heating gas through the vaporizer for heating the walls thereof,
- means for conducting vapor generated externally of the vaporizer through the heating gas within the vaporizer for converting the vapor into a permanent gas, means for mixing the permanent gas with air, and means for conducting the permanent gas thereto.
21. A vaporizing member with a partition forming two communicating chambers therein, a conduit formed in the partition for conveying gas or vapor, and means for conducting a heating gas through said chambers.
22. A base, a vaporizing member with a partition forming two communicating chambers therein, a conduit in said partition, the partition extending below the vaporizing member into the base and forming two chambers in the base which communicate with the chambers in the vaporizing member.
23. A base having an upper cupped portion, a dome surmounting the cupped portion, a vaporizing member above the base and nesting with the dome, a partition in the vaporizing member and base, and a conduit in the partition extending through the top of the vaporizing member.
24. A base having an upper cupped portion, a dome surmounting the cupped portion, a vaporizing member above the base and nesting with the dome, a partition in the vaporizing member and base, and a conduit in the partition extending through the top of the vaporizing member, the conduit extending through the bottom of the base.
25. A base having an upper cupped portion, a dome surmounting the cupped portion, a vaporizing member above the base and nesting with the dome, a partition in the vaporizing member and base, and a conduit in the partition extending through the top of the vaporizing member, the conduit being formed integrally with the partition, the partition being formed integrally with the vaporizing member.
26. A base having an upper cupped portion, a dome surmounting the cupped portion, a vaporizing member above the base and nesting with the dome, a partition in the vaporizing member and base, and a conduit in the partition extending through the top of the vaporizing member, the conduit being formed integrally with the partition, the partition being formed integrally with the vaporizing member, the conduit extending through the bottom of the base, and a nut on the conduit below the base for holding the vaporizer on the base.
27. A base, a dome above the base, a vaporizing member above the base nesting with the dome, means for supplying oil to the external wall of the vaporizing member, means for conducting a heating gas inside the vaporizer to heat the walls thereof and vaporize the oil on its external walls, and a conduit extending longitudinally through the vaporizer and having a great area within

the vaporizer heated by the heating gas within the vaporizer, for conveying the vapor formed externally of the vaporizer through the vaporizer to superheat said vapor and form it into a permanent gas during its passage through said conduit.

28. A base, a dome above the base, a vaporizing member above the base nesting with the dome, a conduit extending longitudinally through the vaporizing member, an oil supply pipe extending up inside the dome and adapted to feed oil to the vaporizer, said oil pipe having a loop externally of the dome, the bend of the loop being but slightly below

the level of the highest point of the oil pipe 15 within the vaporizing member to establish an unvarying head of oil, one run of the loop adapted to discharge the surplus oil, a pipe feeding the loop, and a valve for regulating the amount of oil supplied to the vaporizer. 20

In testimony whereof, I have hereunto set my hand at Los Angeles, California, this 16th day of February, 1906.

WILLIAM H. NEHER.
